CLAIM

The ornamental design for a candle light holder, as shown and described.

DESCRIPTION

FIG. 1 is an axonometric view of a candle light holder showing my new design;

FIG. 2 is an axonometric view thereof;

FIG. 3 is an elevational view thereof;

FIG. 4 is a plan view of one component of the design in an unassembled condition;

FIG. 5 is a top plan view of the ring component of the design in an open position; and,

FIG. 6 is a top plan view of the ring component of the design in a closed position.
